US00D910246S

(12) **United States Design Patent** (10) Patent No.: **US D910,246 S**
(45) Date of Patent: **** Feb. 9, 2021**

(54) **PET HAIR REMOVER APPARATUS**

(71) Applicant: **Weinan Zhang**, Yixing (CN)

(72) Inventor: **Weinan Zhang**, Yixing (CN)

(**) Term: **15 Years**

(21) Appl. No.: **29/751,377**

(22) Filed: **Sep. 21, 2020**

(30) **Foreign Application Priority Data**

Sep. 1, 2020 (CN) 2020 3 0510252

(51) LOC (13) Cl. **30-99**

(52) U.S. Cl.

USPC **D30/159**; D30/158

(58) **Field of Classification Search**

USPC ..... D30/158, 159, 199, 162, 106; 119/625, 119/633, 600, 617, 628, 632, 631, 613, 119/618, 619, 620, 611, 609; 132/126, 132/142, 219, 212, 149, 150, 159-161, 132/163; 30/114, 130, 301, 305, 315, 30/316, 299, 303, 306, 169, 322, 31, 30, 30/279.2, 280, 287, 294, 199, 329-344, 30/346.56, 346.61, 355, 357, 526-528; D7/672-676, 687, 686, 634, 619, 688, D7/653, 395; 425/298; 426/503; D4/136, 127, 124-126, 116-118, 199, D4/194; D32/42, 25, 46; 172/379, 380; D21/532, 398; 56/400.01, 400.1, 400.17, 56/400.21, 400.05, 400.04, 330; 15/402, 15/142, 236.07, 236.08, 236.05, 159.1, 15/160, 171, 176.1, 236.01, 236.02; 601/137, 136, 80, 93, 95, 97, 101, 103, 601/138, 143-147; D8/13, 6, 10, 11, 12, D8/1, 33, 40, 41, 80, 94, 97, 98, 105, D8/107, 300-303, 307, 321; 126/173, 126/214 C, 25 R; D28/46, 48

(57) **CLAIM**

The ornamental design for a pet hair remover apparatus, as shown and described.

DESCRIPTION

FIG. 1 is a front perspective view of a pet hair remover apparatus, showing my design.

FIG. 2 is a rear perspective view thereof.

FIG. 3 is a front elevation view thereof.

FIG. 4 is a rear elevation view thereof.

FIG. 5 is a left side elevation thereof.

FIG. 6 is a right side elevation thereof.

FIG. 7 is a top plan view thereof.

FIG. 8 is a bottom plan view thereof; and,

FIG. 9 is an enlarged view of an area labeled 9 in FIG. 2. The broken lines in the drawings depict environmental structure and boundaries and form no part of the claimed design.

1 Claim, 9 Drawing Sheets
